(57) **CLAIM**

The ornamental design for a vehicle front fender, as shown and described.

DESCRIPTION

FIG. 1 is a side elevation view of the vehicle front fender;
FIG. 2 is a top plan view thereof;
FIG. 3 is a front view thereof; and,
FIG. 4 is a perspective view thereof.

The broken lines shown in the drawings depict portions of the vehicle front fender that form no part of the claimed design.
